RAILWAY-ANCHOR.

No. 858,794.

Specification of Letters Patent.

Patented July 2, 1907.

Application filed November 2, 1906. Serial No. 341,688.

To all whom it may concern:

Be it known that I, HENRY R. COOPER, Sr., a citizen of the United States, residing at Buffalo, in the county of Erie and State of New York, have invented a new 5 and useful Improvement in Railway - Anchors, of which the following is a specification.

This invention relates to the means for preventing spreading of the rails of railways and also bracing the same, and which are generally known as railway anchors or anti-rail spreaders and braces.

The object of this invention is to produce an anchor of this character which effectually prevents spreading of the rails and also reliably braces the same, which is comparatively simple in construction and requires no 15 special tools for applying the same to the rails and which affords the greatest rigidity and stability in proportion to the amount of metal used.

In the accompanying drawings: Figure 1 is a vertical transverse section of a pair of rails connected by my 20 improved anchor taken in line 1-1, Fig. 2. Fig. 2 is a top plane view thereof, partly in section, taken in line 2-2, Fig. 1.

Similar letters of reference indicate corresponding parts in both views.

25 A represents the two rails of a railway each of which is of usual construction and comprises a horizontal base *a*, a vertical web *a*¹ rising from the base and a head *a*² arranged at the upper end of the web.

My improved anchor, whereby these rails are braced 30 and prevented from spreading is constructed as follows: B represents a transverse tie rod or bar which is oblong in cross section and which is bent or twisted to form a central part *b* arranged with its long sides vertically between the rails and end portions *b*¹ arranged with 35 their long sides horizontally and transversely underneath the rails. By this means the tie rod or bar is prevented from being deflected at the center vertically by pressure applied thereto in that direction while the horizontal end portions thereof permit of conveniently 40 attaching thereto the devices which connect the tie bar with the rails.

At the outer ends of the tie bar the same is provided with upwardly projecting walls or shoulders *C* which terminate at their upper ends in bills or beaks *c* which 45 are bent so as to project inwardly therefrom, thereby forming hooks at opposite ends of the tie bar.

On opposite ends of the tie bar are mounted shoes, chairs or seats each of which consists of a horizontal bottom *D* resting on the adjacent horizontal end portion 50 of the tie bar and arranged transversely underneath the base of the adjacent rail, upright walls *d*, *d* projecting upwardly from opposite ends of the bottom and on opposite sides of the rail, and inwardly turned beaks or bills *e* arranged at the upper ends of the walls

55 and forming together with the latter jaws or hooks at opposite ends at the bottom—which have their mouths or open sides facing each other. The outer wall of each shoe bears against the inner side of the adjacent wall of the tie bar and projects underneath the beak of said tie bar wall, thereby preventing these parts from 60 becoming displaced relatively to each other in a vertical direction. Underneath each rail the bottom of the respective shoe is secured to the corresponding end portion of the tie bar by means of a rivet *f*, as shown or by any other suitable means.

65 Between opposite sides of the base and web of each rail and the adjacent shoe are arranged two holding members of substantially U-form which operate to secure the rail to the shoe and also to brace the rail against turning. Each of these holding members comprises a wedge *G* which is driven horizontally between the inner side of one hook of the shoe and the adjacent longitudinal side or edge of the base of the rail, a horizontal lower flange *g* projecting inwardly from the lower part of the wedge and into the space between the underside of the rail and the upper side of the shoe bottom, and an inclined upper flange *g*¹ projecting inwardly from the upper part of the wedge and resting with its under side on top of the adjacent part of the rail base while its inner end bears against the adjacent vertical 75 side of the rail web. The outer part of each wedge is arranged between the bottom of the shoe and the beak of the adjacent shoe end wall which overhangs the wedge. By this means the holding member not only secures the rail to the shoe but a firm and reliable support is furnished for the rail which effectually prevents the same from turning inasmuch as all tendency to displace the wedge vertically is resisted by the beaks of the shoe engaging with the top of the wedge and the lower flange of the wedge engaging with the underside 80 of the rail base.

85 Any suitable means may be employed for holding the wedges in place after the same have been driven firmly between opposite sides of the rail and the shoe. The means preferred for this purpose and shown in the drawings consists of a bendable locking lip or ear *h* which is arranged at the small or narrow end of the wedge and adapted to engage with the side of the adjacent shoe wall. This lip may be formed integrally 90 with the wedge but preferably consists of a piece of sheet 100 iron which is connected at one end with the wedge by placing the same into the mold in which the wedge is to be cast and then pouring the metal in this mold, whereby when the metal is cooled the wedge and the locking lip will be firmly united. While driving the 105 wedge between the rail and the shoe the locking lip is left in a straight condition in which it is arranged lengthwise of the wedge, as shown at the extreme right of Fig.

- 2, and after the wedge has been tightened the free end of the locking lip is bent outwardly against the adjacent side of the shoe wall, as shown at the left of Fig. 2, thereby securely holding the wedge in its tightened 5 position. The tightening of the wedge and the bending of its locking lip are effected by the use of an ordinary maul thus avoiding the necessity of providing special tools for installing this anti-rail spreading and bracing device on railways.
- 10 As shown in Fig. 2, the wedges between opposite sides of the companion rail and shoe are constructed to be driven or tightened in opposite directions lengthwise of the rail. By this means the load moving in either direction over the rails will tend to tighten one 15 wedge or the other, thus preventing loosening of the connections and avoiding creeping or displacement of the tie bar and rails relatively to each other.
- 15 My improved anchor for bracing the rails and preventing spreading of the same can be readily applied 20 to railways without taking up the rails or moving ties and without employing high grade or skilled labor for this purpose.
- I claim as my invention.
1. A railway anchor comprising a tie bar adapted to extend underneath the rails, upright walls arranged at opposite ends of the bar, shoes secured to opposite ends of said bar, and each provided at opposite ends with an inner hook and with an outer hook which bears against the adjacent wall of the bar, and holding members adapted to be 25 interposed between said hooks and a rail, substantially as set forth.
  2. A railway anchor comprising a tie bar adapted to extend underneath the rails, upright walls arranged at opposite ends of the bar and each provided at its upper end 30 with an inwardly turned beak, shoes secured to opposite ends of said bar and each having a bottom, an inner hook and an outer hook bearing against the inner side of one of said walls and projecting underneath the beak thereof, and holding members adapted to be interposed between said 35 hooks and a rail, substantially as set forth.
  3. A railway anchor comprising a tie bar, shoes for receiving rails secured to opposite ends of said bar and each having a horizontal bottom and hooks at opposite ends of the bottom, and wedges adapted to be driven between said 40 hooks and opposite sides of each rail, substantially as set forth.
  4. A railway anchor comprising a tie bar, shoes for receiving rails, secured to opposite ends of said bar and each having a horizontal bottom and hooks at opposite ends of the bottom, and wedges adapted to be driven in opposite directions between said hooks and opposite sides of each rail, substantially as set forth.
  5. A railway anchor comprising a tie bar, a holding member of U-form having flanges adapted to engage with 45 the upper and lower sides of the base of the rail, and means for supporting said holding member on said bar, substantially as set forth.
  6. A railway anchor comprising a tie bar adapted to extend transversely underneath the rails, shoes secured to opposite ends of said bar and each having a bottom adapted 50 to be arranged under a rail and hooks at opposite ends of
- the bottom, and two holding members each of which is U-shaped and adapted to be interposed between one of said hooks and said rail having a lower flange which bears against the underside of the base of the rail and an upper flange which bears against the upper side of the base of the rail, substantially as set forth. 65
7. A railway anchor comprising a tie bar adapted to extend transversely underneath the rails, shoes secured to opposite ends of said bar and each having a bottom adapted to be arranged under a rail and hooks at opposite ends of the bottom, and two holding members each of which is U-shaped and adapted to be interposed between one of said hooks and said rail having a lower flange which bears against the underside of the base of the rail and an upper flange which bears against the upper side of the base of the rail and also against the web of the rail, substantially as set forth. 70
8. A railway anchor comprising a tie bar adapted to extend transversely underneath the rails, shoes arranged at opposite ends of the bar, and a holding member consisting of a wedge adapted to be arranged between the outer edge of the rail base and said shoe, a lower flange projecting from said wedge inwardly underneath said base and an upper flange projecting inwardly from said wedge over said base, substantially as set forth. 75
9. A railway anchor comprising a tie bar adapted to extend transversely underneath the rails, shoes arranged at opposite ends of the bar, and a holding member consisting of a wedge adapted to be arranged between the outer edge of the rail base and said shoe, a lower flange projecting from said wedge inwardly underneath said base and an upper flange projecting inwardly from said wedge over said base, substantially as set forth. 80
10. A railway anchor comprising a tie bar adapted to extend transversely underneath the rails, shoes arranged at opposite ends of the bar, wedges adapted to be driven between the rails and said shoes, and a locking lip arranged on the small end of said wedges and adapted to be bent into engagement with the side of said shoes, substantially as set forth. 85
11. A railway anchor comprising a tie bar adapted to extend transversely underneath the rails, upright walls arranged at the ends of the bar and having inwardly turned beaks at their upper ends, shoes secured to opposite ends of the bar and each having a bottom, an inner hook and an outer hook which engages with the adjacent wall and projects underneath the beak thereof, holding members arranged between opposite sides of each rail and the adjacent 90 shoe and each having a wedge which is adapted to be driven between the inner side of a hook and the edge of the rail base, a lower flange projecting inwardly from the wedge and underneath the rail base and an upper flange projecting inwardly from the wedge over the underside of the rail base and against the web of the rail, said wedges being constructed to tighten when driven in opposite directions, and locking lips set into the small end of said 95 wedges and each adapted to be bent laterally outward against the side of the adjacent hook, substantially as set forth. 100
12. A railway anchor comprising a tie bar adapted to extend transversely underneath the rails, upright walls arranged at the ends of the bar and having inwardly turned beaks at their upper ends, shoes secured to opposite ends of the bar and each having a bottom, an inner hook and an outer hook which engages with the adjacent wall and projects underneath the beak thereof, holding members arranged between opposite sides of each rail and the adjacent 105 shoe and each having a wedge which is adapted to be driven between the inner side of a hook and the edge of the rail base, a lower flange projecting inwardly from the wedge and underneath the rail base and an upper flange projecting inwardly from the wedge over the underside of the rail base and against the web of the rail, said wedges being constructed to tighten when driven in opposite directions, and locking lips set into the small end of said 110 wedges and each adapted to be bent laterally outward against the side of the adjacent hook, substantially as set forth. 115
13. A railway anchor comprising a tie bar adapted to extend transversely underneath the rails, upright walls arranged at the ends of the bar and having inwardly turned beaks at their upper ends, shoes secured to opposite ends of the bar and each having a bottom, an inner hook and an outer hook which engages with the adjacent wall and projects underneath the beak thereof, holding members arranged between opposite sides of each rail and the adjacent 120 shoe and each having a wedge which is adapted to be driven between the inner side of a hook and the edge of the rail base, a lower flange projecting inwardly from the wedge and underneath the rail base and an upper flange projecting inwardly from the wedge over the underside of the rail base and against the web of the rail, said wedges being constructed to tighten when driven in opposite directions, and locking lips set into the small end of said wedges and each adapted to be bent laterally outward against the side of the adjacent hook, substantially as set forth. 125

Witness my hand this 19th day of October, 1906.
